Primary Examiner — Vy N Koenig(57) **CLAIM**

The ornamental design for a tripod for camera phones, as shown and described.

DESCRIPTION

FIG. 1 is a perspective view of a tripod for camera phones showing my new design.

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof;

FIG. 8 is a front view illustrating the tripod for camera phones of FIG. 1 in an alternate collapsed state; and,

FIG. 9 is a side view illustrating the tripod for camera phones of FIG. 1 in an alternate collapsed state.

The surface ornamentation shown in broken lines in FIGS. 1, 2, 4, 5 and 9 depicts environmental subject matter and forms no part of the claimed design.

1 Claim, 3 Drawing Sheets(56)
